UNITED STATES PATENT OFFICE.

EARL V. SALA, OF TOLEDO, OHIO.

ENGINE.

1,327,172.

Specification of Letters Patent.

Patented Jan. 6, 1920.

Application filed March 12, 1917. Serial No. 154,127.

To all whom it may concern:

Be it known that I, EARL V. SALA, a citizen of the United States, and a resident of Toledo, in the county of Lucas and State of Ohio, have invented a certain new and useful Engine; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

My invention relates to internal combustion engines and it has for its object to provide an engine which may be made at a low cost of production and yet one which is exceedingly efficient and has a very small number of movable parts. It particularly has for its object to provide a silent running engine wherein the cylinders may be charged with the explosive mixture and wherein the products of the combustion may be completely discharged at the minimum amount of loss of energy in the operation of the engine.

By my invention a means is provided for rapidly opening the passageways which terminate in large valve areas for the fuel and burnt gases to their fullest extent. Also, a means is provided whereby the passageways leading to and from the engine during the periods of the exhaust and the intake will be completely opened at the times that the engine in its cycles of operation is ready to receive or eject the materials contained in the cylinders. Also, in constructions containing my invention, the explosive mixture is heated by the heat of the exhaust products and, consequently, the passageways through which the ejected products pass are correspondingly cooled. Also by my invention an effective means is provided for sealing the cylinder during the compression and power strokes from any possible leakage. Also, by my invention the openings of the ports are positively performed by mechanical means and are not dependent upon the yielding operation of elastic means.

The invention may be contained in many forms of engines usable for different purposes, all of which come within the purview of my claims hereinafter appended. To show the practicability of my invention, I have selected one form of engine as an

example and shall describe it hereinafter. The construction selected is illustrated in the accompanying drawings.

In the figures, Figure 1 is a side view of parts of the engine and a vertical sectional view taken through the valve members of the engine, the piston rods and valve rods being shown interconnected diagrammatically. Fig. 2 is a horizontal sectional view taken through the line 2—2 indicated in Fig. 1 and Fig. 3 is a vertical sectional view taken through the broken line 3—3 indicated in Fig. 2. Fig. 4 is a side view of the engine cylinders. Fig. 5 is a diagrammatic illustration of the cyclic operations of the engine.

1, 2, 3 and 4 indicate engine elements, that is, the parts of the engine which coöperate to control the engine gases and which are operated by the explosion of the gases.

The engine is provided with a casing 10 which is common to all of the elements for inclosing the crank shaft and piston rods. It is provided with the portion 11 which is bolted to the cylinder casing 12 and the lower portion 13 which is bolted to the portion 11.

The lower part of the casing 10 is provided with a crank shaft 15 which extends between the parts 11 and 13 and is supported in suitable bearings. The piston rods 17 are connected to the crank shaft 15 and to the engine pistons 23. The pistons are provided with the rings 19 which seal the interior of the cylinder from leakage during the times of the explosion and the compression. The cylinder casing 12 is provided with a suitable jacket having the chamber 18 for containing water or other cooling medium for reducing the temperature of the engine.

Piston valve members 31, 32, 33 and 34 are located within the casing 12 of the engine. The piston valve members are longitudinally movable in the engine casing 12. They are positively operated by the crank shaft of the engine or by some other means which will synchronously operate the piston valve members with respect to the movements of the piston. The piston valve members may be driven by a sprocket gear located on the crank shaft 15. The crank shaft 15 is connected to a crank shaft by means of a sprocket chain 27 and a sprocket gear. The crank shaft is connected to rods 35 which are connected to pairs of ears 36 extending from the pistons 31, 32, 33 and 34. The engine cylinders are provided with

ports and the engine casing and the piston valve members are provided with passageways for controlling the flow of the fuel and burnt gases of the engine. The connections between the pistons of the engine and the valve members are such that they move in a two-to-one relation, that is, the pistons make two strokes in a given direction, while the valve members make a short single stroke. The strokes of the valve members are such that they quickly open the passageways of the engine to their widest extent and quickly close them while the pistons are performing their operations in the cycles of the engine elements.

The valve members 31, 32, 33 and 34 extend to near the top of the casing. The casing is provided with plates 37 which are bolted onto the top of the engine. The casing 12 is provided with passageways 41, 42, 43 and 44 for the burnt gases and also passageways 51, 52, 53 and 54 which communicate with the fuel supply of the engine. The ignition plugs 56 are inserted in the engine cylinders and extend into the explosion space 47 whereby the explosive charges are ignited at the beginning of the power stroke in the manner well known in the art.

The cylinders of the engine in which the valve members move and the cylinders in which the engine pistons move are arranged in pairs. The passageways 41 to 44 and the passageways 51 to 54 which communicate respectively with the exhaust and intake manifolds of the engine, are controlled by the movable piston valve members 31 to 34, respectively. The openings 61, 62, 63 and 64, formed in the valve members, are adapted to register, either with the exhaust passageways 41 to 44 or with the intake passageways 51 to 54, respectively. The openings 41 to 44, 51 to 54 and 61 to 64 permit the gases to pass to and from the engine cylinders, that is, to and from the other cylinder 45 of the pair in which each cylinder is coupled or associated. The arrangement may be such that the openings or ports 61 to 64 will register with the passageways 41 to 44 when the valve members have completed 50 movements in one direction and to register with the passageways 51 to 54 when the valve members have completed their opposite movements.

The ports or openings 71, 72, 73 and 74 in the casing permit the gases to enter and exhaust from the cylinders. By this means the passageways leading to each engine cylinder from the source of fuel supply and the passageways which lead to the exhaust 60 of the engine, from each engine element are controlled by the movements of two valve members, that is, one of the openings 61 to 64 in a valve member controls the direct communication between an engine cylinder 65 and the manifolds, while one of the open-

ings 71 to 74 in the casing coating with another of the piston valve members controls the communication between the engine cylinders and the passageways which are subject to the control of the first set of openings. The second set of openings and valve members controls the passageways which lead from the engine cylinder of the pair in which it is associated, which controls the direct communication leading to and from 75 the exhaust and intake of the engine also controlled by the first set of openings.

The passageways 81, 82, 83 and 84 interconnect between the engines in pairs. They extend through the engine casing and through the valve members. They terminate in the openings 61 to 64 and 71 to 74. The passageway 81 leads from the exhaust and intake passageways 42 and 52 of the engine element 2 to the engine cylinder of 85 element 1, while the passageway 82 leads to and from the engine element 1 having passageways 41 and 51. Also, the passageways 83 and 84 interconnect the engine elements 3 and 4 in the same manner.

The piston valve members 31 to 34 are each provided with a small neck 91 interconnecting two enlarged cylindrical portions 92 and 93. The extensions of the passageways 83 are through the portions 92 of the valve members. The valve members are made hollow and the passageways 83 in the portions 92 are separated from the rest of the interior of the valve members by the partitions 94. Above and below the openings 61 to 64 which terminate the passageways 81 to 84, and in the enlarged portions 92 are located piston rings. In the portions 93 are located broad piston rings 95. The portions 92 open and close one end of the passageways 81 to 84 by opening and closing the openings 61 to 64, and the portions 93 open and close the other end of the passageways by opening and closing the openings 71 to 74 in the casing. The ends 110 of the valve members are connected together by tubular passageways 96. Oil may be fed to the top of the valve members, and allowed to pass down through them. The restricted passageways 96 will operate to suck and work the oil back and forth and downwardly across the passageways 81 to 84 in which the tubular walls of the passageways 96 are located. The top of the engine cylinder communicates with the valve member cylinder through the port 97 which is located at a point intermediate the portions 93 and 94 of the piston valve members.

The openings 71 and the valve members 31 control the connection 81 leading from the passageways 42 and 52, while the passageways 42 and 52 are controlled by the opening 62. The intake of the charging gas and the exhaust of the products of combustion of the engine element 1 is thus depend-

ent upon, not only the movements of the valve member 31, but also the movements of the valve member 32. The openings 71 to 74 are so located as to be 200° in advance of the opening of the intake passageways of the engine elements of which they form a part, that is, the opening 71 is such that it begins to open the passageway 81 at 200° in advance of the time in which the opening 61 opens the intake passageway 51. Also, the opening 71 is of such size and so located in the cylinder 31 that the passageway 81 is closed 20° behind the closing of the passageway 51. The opening ports of the exhaust passageways being 180° from the opening ports of the intake passageways a corresponding relation exists between the opening and closing of the ports to the interior of the cylinder above the pistons. The openings 71 to 74 are located 110° as measured in the circle described by the crank pins of the shaft of the valve members in advance of the opening of the intake of the engine cylinders of the pairs in which they are associated, that is, the opening 71 begins to open the passageway 81, 110° in advance of the opening of the intake passageway 52 to the valve member 32, or 220° as measured in the circular movements of the engine crank pin of the element 1. The openings 71 to 74, however, are 70° after the openings of the exhaust passageway, of the cylinders of the other of the engine elements in the associated pairs, take place, that is, the opening 71 begins to open the passageway 81, 70° after the opening 62 of the valve member 32 begins to open the exhaust 42.

The engine elements are connected to the crank shaft at points 90° ahead of each other. The pistons of the engine elements are connected to the crank shafts so as to perform in a certain sequence the cyclic operations of each engine element. In the form shown the engine element 3 follows in sequence the engine element 1 and then the engine element 4 follows in the performance of the same operation of the cycle and then the engine element 2 follows the performance of the engine element 4, so that the engine elements in the order of 1, 3, 4 and 2, perform the four cycles.

As shown in Fig. 5, the driving stroke of the engine piston of the element 1 moves the crank pin from the radial line A to the radial line B. Meantime, the connection 81 is opened by the valve member 31 which, as indicated by the circular movements of the crank pin of the valve member of the element 2 passes from the radial line A to the radial line B and when it reaches B the connection 81 is closed. The cylinder 32 has also been moving from a point measured on the crank pin from the radial line A to the radial line B, during which time the intake

passageway is open to the connecting passageway 81. So that, while the crank pin of the engine 1 passes from the radial line A to the radial line B, the intake passageway leading through the connection 81 and the openings 62 and 71 have been opened, and, although during that movement the piston 31 performs a part of its return, yet the low pressure created within the cylinder 31 by the downstroke of the piston of the engine 1 still draws the explosive mixture through the passageways 52 and 81 which convey the explosive mixture from the manifold through the valve member 31 until the communication is cut off by the valve member 31, which occurs when the crank pin of the piston of the engine moves across the radial line B. It thus has an intake, in this construction, while the crank pins of the engine are moving 220° .

As the crank pin of the piston of the engine element 1 moves from the radial line A to the radial line B, the port 61 is open and closes when the crank pin reaches the radial line B, although the opening 52, which communicates with the manifold leading from the carburetor, is opened until the crank pin reaches the radial line A, C. During the time of the movement of the crank pin from the radial line B to the radial line A, C, the piston of the engine 1 is compressing. Shortly after the movement of the crank pin through the radial line A, C, the explosion takes place and drives the piston until the crank pin passes through the radial line D. When it passes through the radial line D the port 71 opens the connection 81. The exhaust port 42, however, has by this time been opened and was opened when the crank pin passed the radial line A, C, namely, when the crank pin of the valve member 31 is at C. While the crank pin of the engine 1 passes across the radial line D to the radial line A the port 71 is open and also the exhaust port 42 is open, whereby the products of combustion pass out through the ports 71 and 62 through the exhaust passageway 42. The exhaust ports of the engine are thus opened while the engine crank pins describe 220° in the construction described. When the crank pin of the engine 1 passes through the radial line A, C the port 61 again begins to open the passageway 52 and the gases begin to pass in through the ports 71. The gas continues to pass into the valve member 31 as before notwithstanding the fact that the piston of the engine 1 has begun to return owing to the vacuous condition produced in the sleeve by the outward movement of the piston.

The same cycle of operations is performed by the other engine elements which are thus inter-related in pairs, the sequential operations of the engine elements 1, 3, 4, 2 being

in the order ennumerated and 90° apart. The same angular relation existing between the ports of each valve member in their opening and closing throughout the engine elements, 5 there is also a uniform corresponding angular relation of the ports of the valve members of the engines of the associated pairs so that all of the engine elements will perform the same operation as described in connection with the engine elements 1 and 2.

10 The passageways 41 to 44 and 51 to 54 are connected to the manifolds 65 and 67. The exhaust manifold 65 is secured to the casing 12 by means of bolts while the manifold 67 for the explosive mixtures is secured to the casing 12 by means of bolts and is connected to the carbureter 68.

I claim:

20 1. In an engine, the combination of an engine cylinder, a pair of piston valves, each piston having heads and a passageway in one of the heads, a valve cylinder for each of the valves, the engine having a port connecting the engine cylinder with one of 25 the valve cylinders intermediate the heads, the passageway to the port controlled by both valve pistons.

2. In an engine, the combination of a pair

of engine pistons, a pair of valve members, each valve member having a passage-way 30 extending through the body of the valve member for controlling the intake and exhaust gases, and a passage-way extending through the body of the valve member for controlling the intake and exhaust gases that 35 pass through the passage-ways of the other valve member.

3. In an engine the combination of a casing, a pair of pistons, a pair of valve members, the casing having a pair of engine cylinders and a pair of valve member chambers and a plurality of passageways, one passageway connecting each valve member chamber with its associated engine cylinder, two other of said passageways for 45 connecting the valve member chambers for connecting intake and exhaust gases from one chamber to the other and another of said passageways for intake and exhaust gases connected to each valve chamber, the valve 50 members having passageways for controlling the flow of the intake and exhaust through the passageways of the casing.

In testimony whereof, I have hereunto signed my name to this specification.

EARL V. SALA.
